UNITED STATES PATENT OFFICE.

EDWIN J. AKINS, OF MOUNDSVILLE, WEST VIRGINIA.

SUPERHEATER.

1,093,519.

Specification of Letters Patent. Patented Apr. 14, 1914.

Application filed November 29, 1912. Serial No. 734,032.

To all whom it may concern:

Be it known that I, EDWIN J. AKINS, a citizen of the United States, and a resident of Moundsville, in the county of Marshall and State of West Virginia, have invented a new and Improved Superheater, of which the following is a full, clear, and exact description.

This invention relates to improvements in superheaters, and particularly to superheating devices connected to and designed to be used in conjunction with traction engines.

The object in view is to provide a superheating device for utilizing the waste heat from a traction engine or similar machine, for superheating the exhaust steam and again utilizing the same in any desired manner, as for instance, in a low pressure cylinder.

A further object of the invention is to provide in a traction engine a superheater device formed with a housing arranged preferably on top of the engine and designed to have passed therethrough smoke and heated products of combustion after the same have left the flues of the engine. This housing includes a plurality of steam pipes carrying live steam and exhaust steam which is superheated for providing a maximum energy to be exerted on both the low and high pressure cylinders connected with both the live and exhaust steam respectively.

In carrying out the objects of the invention, a steam traction engine of any desired kind is provided, to which is secured a housing, the housing being preferably arranged on top of the boiler and extending for substantially the full length and merging into the smoke stack at the front. An independent smoke stack is provided with the housing at the end opposite the ordinary smoke stack and dampers or covers are provided for both smoke stacks so that the draft may be directed to either stack and consequently caused to pass either directly into the atmosphere from the flues of the boiler, or longitudinally through the shell or superheater housing to the auxiliary smoke stack. A dome is provided in the superheater housing, formed substantially of an enlarged tube or pipe connected at both ends to the boiler so that the same will be receiving live steam regardless of the angle at which the engine is traveling, and the steam will be maintained in a dry or superheated condition by the hot gases passing out of the second or auxiliary smoke stack.

In order to emphasize or to insure the proper temperature in the live steam, the same is taken out from substantially a central point of the dome and passed through a coiled pipe arranged in the superheater housing before the same is discharged into the cylinder of the engine. In this way dry steam is provided for the cylinder of the engine, which cylinder is designed to exhaust into a second coiled pipe arranged in the superheater housing, which exhaust steam is directed or guided to a low pressure cylinder. In this way the steam, either live steam or exhaust steam, is caused to enter the respective cylinders of the engine at the highest possible temperature so as to provide the greatest possible energy with a given amount of heat generated in the fire box.

A practical embodiment of the invention is represented in the accompanying drawings forming a part of this specification, in which similar characters of reference indicate corresponding parts in all the views.

Figure 1 is a longitudinal vertical section through the boiler and part of the frame of a traction engine and a superheater embodying the invention; Fig. 2 is a section through Fig. 1 approximately on the line 2—2; Fig. 3 is a section through Fig. 1 on the line 3—3; and Fig. 4 is a view of a boiler and the superheater housing surrounding the same, together with the superheater coil, this view disclosing a slightly modified form of the invention, whereby the housing entirely surrounds the boiler barrel thus causing the smoke and unburned products of combustion to return in a spiral path or long travel distance.

Referring to the accompanying drawings by numerals, 1 indicates a frame of any desired kind provided with suitable supporting traction wheels 2 propelled by engines 3 and 4, which are provided with cylinders 5 and 6, the cylinder 5 being a high pressure cylinder, and the cylinder 6 being a low pressure cylinder.

The detail construction of the cylinders, engines, and frame 1, may be of any form, as the same form no part of the present invention, being shown to display the advantages of the superheater forming the invention.

Mounted on the frame 1 is a boiler 7 having a fire box 8 of any usual or preferred kind. The boiler 7 is provided with a front chamber 9 which is usual in boilers of this

kind, the chamber 9 opening into a smoke stack 10. The smoke stack 10 is provided with a cover 11 pivotally mounted so as to be operated by a rod 12. The smoke stack 5 merges into and forms part of a superheater housing 13 which extends preferably for the full length of the boiler 7 and is provided with an auxiliary stack 14. The stack 14 has associated therewith a pivotally 10 mounted cover 15 designed to be operated by a rod or link 16. The lower part of the housing 13 may be secured directly to the boiler 7, as shown in Fig. 3, or may be bent around and connected together so as to define an independent housing or tube. From the construction just described it will be seen that the smoke and hot products of combustion may pass out stack 10 when the lid or cover 11 is open, but when the lid or 15 cover is closed the smoke and hot products of combustion will pass out stack 14, the cover thereof being, of course, held open.

In traction engines it is often found necessary to transport the same over roads or 20 other places having a greater or less amount of grades so that special means must be provided for directing the steam to the cylinders of the engine. According to the present arrangement a dome 17 is provided 25 which is connected by suitable pipes 18 and 19 to the opposite ends of the boiler 7 so that if one of the pipes is covered with water the other pipe will be feeding steam to the dome and thus maintain a proper pressure 30 in the dome from which the steam is directed to the engine. One end of the dome is closed, while the other end is provided with an aperture designed to receive pipe 35 20, which pipe projects to a central point 40 in the dome but does not fit snugly the dome so that there is ample space around pipe 20 for steam from pipe 16 to enter the dome. By this construction and arrangement a substantially even pressure of steam is provided 45 for pipe 20 which has connected therewith a superheating pipe 21 coiled around dome 17 and finally connected with the discharge pipe 22 connected with the steam chest of cylinder 5. After the steam from 50 pipe 22 has been utilized in the high pressure cylinder 5, the same is exhausted into pipe 23 and from thence it is discharged into a coiled pipe 24 which is arranged in housing 13 so that the exhaust steam is thus 55 superheated or again raised in temperature. The steam from coil 24 passes into a discharge pipe 25, and discharge pipe 25 leads to the low pressure cylinder 6. The exhaust from low pressure cylinder 6 may be 60 directed to the atmosphere or to either of the smoke stacks, as desired, for assisting the draft.

In starting there is of course no steam in the pipe 25, or at least there is only a small 65 amount of steam even after the cylinder 5

has exhausted therein so that under such circumstances the low pressure cylinder 6 would be of little use. However, in order to overcome this objection, the pipes 20 and 25 are connected to a fitting 26 which has an enlargement 27. The enlargement 27 carries a puppet valve 28 designed to be set so as to be opened at any desired pressure. The puppet valve 28 could be, for instance, set so as to close when the pressure in pipe 25 was half that in pipe 20. If the puppet valve was set for operating in this manner the low pressure cylinder would be provided with live steam at the time of starting with the pressure half that of the high pressure cylinder so that substantially a maximum impulse is provided at the starting. As the high pressure cylinder exhausts into the coil 24 the amount of live steam supplied to pipe 25 will be gradually diminished until there is substantially no live steam supplied and thus a minimum amount of steam will be used while a maximum result will be obtained.

When first starting the fire the cover 11 is raised and cover 15 is closed so that a direct draft will be provided. After the fire has been properly started the cover 11 is closed and the cover 15 opened so that the draft will be through the housing 13. After the proper amount of steam has been raised and it is designed to start the engine, the manually operated valve 29 is opened so as to allow the live steam to pass through the puppet valve 28 into the pipe 25. After this has been done the steam is turned on to the cylinders 5 and 6 in any desired way and live steam will be utilized in both cylinders until the exhaust from the high pressure cylinder 5 will be sufficient for supplying the low pressure cylinder 6 with steam. When this occurs the valve 28 automatically closes under the pressure of the steam. If desired, the valve 29 could be closed also. In connection with these superheating coils and the domes, it will be observed that the same is arranged on top of the boiler 7 so as to receive any heat radiating therefrom as well as the heat from the smoke and hot products of combustion pipes. It will also be noticed that this superheater covers or protects the upper part of the boiler and consequently prevents the radiation at that point.

In Fig. 4 will be seen a slightly modified form of the invention, in which the front part of the boiler 7 is surrounded by a housing 13' which thus receives heat by radiation from the boiler as well as from the smoke and hot products of combustion designed to be directed through the smoke stacks 10 and 14 respectively. In this form of the invention the boiler 17 is mounted in the same manner as shown in Fig. 1, but the superheating coil 30 is wound or passed

around the entire boiler so as to receive a maximum amount of heat therefrom. In this form of the invention it will be observed that the steam may be taken directly 5 from the boiler 7 by the pipe 31 or may be caused to pass through the superheating coil 30 and be discharged out pipe 32. The pipes 31 and 32 may be connected to one or more cylinders in any desired manner, 10 the same not forming any part of the invention.

Having thus described my invention, I claim as new and desire to secure by Letters Patent:—

15 1. In a superheater device for traction engines, the combination with the boiler of a traction engine, of a steam dome connected to the upper part of said boiler and in free communication with the upper part of the 20 interior of the boiler, means for directing steam from said steam dome to a point of discharge, and exhaust reheating coil surrounding said dome, and means for automatically connecting said dome and said 25 coil for maintaining a predetermined pressure in said coil.

2. In a superheater for engines, the combination with a boiler, of a dome connected at the upper part of said boiler whereby the 30 same is adapted to receive steam regardless of the angle of said boiler, means for directing steam from said dome to a point of utilization, an exhaust reheating coil arranged adjacent said dome, means for directing the exhaust from said point of utilization to said superheater coil, and means for directing the steam from said exhaust reheating coil to a second point of utilization.

3. In a superheater for engines, the combination with a boiler, of a steam dome connected with said boiler, a pipe entering said dome and extending to an appreciable distance therein, a superheater coil connected with said pipe, means for discharging steam 45 from said superheater coil, means for receiving the exhaust from said superheater coil, an exhaust reheating pipe extending for substantially the full length of said dome for receiving said exhaust steam, and 50 a pipe for discharging said steam to a second point of discharge.

4. In a superheater of the class described, the combination with a boiler, of a steam dome connected with said boiler, and a 55 superheater pipe connected with and surrounding said steam dome.

5. In a superheater of the class described, the combination with a boiler, of a steam dome positioned adjacent said boiler, means 60 for connecting said steam dome with said boiler, a superheater coil connected with said dome, means for directing the steam from said superheater coil to a point of utilization.

tion, an exhaust reheating coil surrounding said superheater coil, means for directing 65 the exhaust from said point of utilization to said exhaust reheating coil, and a pipe connected with said exhaust reheating coil for directing the steam to a second point of utilization.

70 6. In a superheater of the class described, the combination with a boiler, of a dome arranged near said boiler, an exhaust reheating coil surrounding said dome, and automatic means for maintaining a certain pressure in said exhaust reheating coil.

75 7. In a superheater of the class described, the combination with a boiler, of a steam dome connected with said boiler and arranged adjacent thereto, means for directing 80 the steam from said dome to a point of utilization, an exhaust reheating coil surrounding said dome, means for directing the exhaust from said point of utilization into said coil, means for directing the steam from 85 said coil to a second point of utilization, connecting pipes for connecting said dome and said coil, and means for regulating the amount of steam passing from said dome to said coil through said connecting pipes 90 whereby the pressure in said coil will bear a predetermined relationship to the pressure in said dome.

95 8. In a superheater of the class described, the combination with a boiler, of a dome connected with the boiler, means for connecting the opposite ends of said dome with said boiler, said means entering said boiler adjacent the opposite ends thereof, a pipe 100 extending through one end of said dome into and to substantially a central point whereby steam is distributed from the center of the dome to said pipe, a superheater coil connected with said pipe adjacent said dome, means for directing steam from said superheater coil to a point of utilization, an exhaust reheating coil surrounding said dome, means for directing the exhaust from said point of utilization to said exhaust reheating coil, means connected with said second 105 exhaust reheating coil for directing the steam therefrom to a second point of utilization, means for connecting the pipe extending into said dome and said exhaust reheating coil whereby steam may pass from said dome into said exhaust reheating coil, and means for regulating the amount of steam passing from said dome into said exhaust reheating coil.

110 115 In testimony whereof I have signed my name to this specification in the presence of two subscribing witnesses.
